LUGGAGE CARRIER OR THE LIKE

Royce L. Raye, 3448 Gladiolus Lane, Dallas, Tex.

Filed Nov. 13, 1963, Ser. No. 77,399

Term of patent 14 years

(Cl. D14—3)

FIGURE 1 is a rear perspective view of a luggage carrier or the like showing my new design;

I claim:

The ornamental design for a luggage carrier or the like, substantially as shown.
